EMBALMING MATERIALS

Charles A. Noll, Philadelphia, Pa., assignor of
one-half to Ralph M. Hibbs, Philadelphia, Pa.

No Drawing. Application January 10, 1947,
Serial No. 721,483

14 Claims. (Cl. 27—22)

1

This invention relates to materials and compositions for embalming and methods of utilizing such materials, and particularly to quaternary ammonium compounds and compositions containing the same for such purposes.

Heretofore, various oils and formaldehyde and formaldehyde mixtures have been used to preserve dead bodies. Preservation by means of such materials depends upon the embalming fluid uniting with the protein in the dead body as well as killing bacteria which may be present. Coagulation or precipitation of the protein in such action is known as "firming action" or fixing. It is characterized by the various parts of the body becoming stiff or hard to the touch.

The old types of embalming agents are unsatisfactory from a number of standpoints. They are toxic and must be handled with extreme care. Formaldehyde materials particularly have a very offensive odor and attempts to mix such materials with substances to disguise such odor have not been satisfactory.

While recent suggestions in the prior art for the utilizing of embalming compositions containing incompletely substituted quaternary ammonium compounds have exhibited some improvement over prior art materials, but still did not satisfy all of the requirements for such materials because those proposals require the inclusion of substantial amounts of formaldehyde with such incompletely substituted quaternary ammonium compounds in order to obtain satisfactory results.

Among the objects of the present invention is the production of embalming materials which may be utilized by themselves to secure satisfactory embalming functions without requiring the utilization of formaldehyde or similar types of materials with them.

Further objects include methods of utilizing such compositions for embalming purposes.

Still further objects and advantages of the present invention will appear from the more detailed description set forth below, it being understood that such more detailed description is given by way of illustration and explanation only, and not by way of limitation, since various changes therein may be made by those skilled in the art without departing from the scope and spirit of the present invention.

In accordance with the present invention embalming compositions are utilized which contain non-poisonous quaternary ammonium compounds that are tetra-organo substituted ammonium halides desirably utilized in an aqueous vehicle.

Embalming of dead bodies can be efficiently accomplished with such materials. The protein in the dead body is firmly fixed by such materials and the action can be carried out by simple compositions under conditions that are readily utilized. Thus from 5 to 50% of the tetra-organo substituted ammonium halide in an aqueous vehicle may be readily employed, particularly at temperatures of from 70° to 110° F. as an embalming agent.

The action of the stated quaternary ammonium compounds can be enhanced and materially improved by utilizing with them water-soluble inorganic salts which are compatible with the quaternary ammonium compounds and which salts also have the property of precipitating proteins. As exemplifying such water-soluble salts there may be mentioned the alkali metal and ammonium sulfates and acid sulfates, sulfites and acid sulfites, and various phosphates and acid phosphates including for example, the metaphosphates. While varying amounts of such inorganic salts may be incorporated into the composition, desirably there is used from 0.5 to 20% of such inorganic salt based on the total weight of the composition. Specifically such salts may be sodium sulfite, sodium acid sulfite, sodium sulfate, sodium acid sulfate, and sodium metaphosphate.

The tetra substituted ammonium halides that may be utilized in accordance with the present invention may be generally formulated as follows

35

in which R₁ and R₂ are desirably lower alkyl radicals or aryl groups and R₃ is desirably a lower alkyl group, aryl, alkenyl, alkoxy or aralkyl where the alkyl again is a lower alkyl group, and H_a is a halogen. The lower alkyls are particularly methyl, ethyl, etc., while the halogens are desirably chlorine or bromine. T in this formulation may be alkyl more particularly a long chain alkyl group, for example, having more than 7 carbon atoms, as for example, lauryl or similar groups obtained from coconut oil, or T may be aryl or may be the group R₄—X—Ar—O—alkylene, in which R₄ is an alkyl, aryl, aralkyl or halogen aralkyl, the alkyl groups in the aralkyl and halogen substituted aralkyl groups desirably being a lower alkyl; Ar is a benzene residue or substituted benzene residue,

55

X is a bridging group, O is oxygen, and alkylene is a lower aliphatic alkylene group.

The aryl trialkyl ammonium halides may be formulated generally as follows:

in which Ar is aryl, R₁ and R₂ are desirably alkyl, preferably lower alkyl groups such as methyl, ethyl, etc., and R₃ is also alkyl but preferably a long chain alkyl having more than 7 carbon atoms such as lauryl as pointed out above.

The tetra-alkyl ammonium halides may be generally formulated as follows

in which R₁, R₂ and R₃ are alkyl groups preferably lower alkyl groups, while R₅ is an alkyl desirably a long chain alkyl having more than 7 carbon atoms, such as lauryl, or other groups as pointed out above. Ha is halogen desirably in all of these formulations, chlorine or bromine.

The alkylene containing tetra substituted ammonium halides may be generally formulated as follows

in which R₁, R₂ and R₃ have the designations for similar groups as set forth above in connection with the first formulation, Ha is halogen desirably chlorine or bromine, alkylene is a lower aliphatic alkylene group such as —CH₂—CH₂—, O is oxygen, Ar is a benzene residue or substituted benzene residue, X is a bridging group such as —CH₂— or —CHR₄— and R₄ is an organic hydrocarbon or substituted hydrocarbon radical more particularly alkyl, such as methyl, ethyl, propyl, etc., or a cyclo aliphatic group such as cyclohexyl, or an aralkyl such as phenyl alkyl, or a substituted aralkyl group such as halogen-phenyl alkyl, the aralkyl and substituted aralkyl groups desirably being those of alkyls of the lower aliphatic series. R₃ may be alkoxy or an aralkyl group such as a phenyl alkyl group particularly where the alkyl group is a lower alkyl group.

As exemplary of quaternary ammonium compounds that may be utilized and are particularly useful in connection with the present invention there may be mentioned lauryl dimethyl benzyl ammonium chloride, lauryl trimethyl ammonium bromide, and lauryl dimethyl ethyl ammonium bromide, or mixtures of two or more of these particular quaternary ammonium compounds. Any number of quaternary ammonium salts may be utilized in admixture if desired, particularly those specifically set forth immediately above and may be utilized as indicated in concentrations of from 5 to 50% by weight in an aqueous vehicle which may be water alone or may include organic liquid solvents miscible with water and compatible with the halide, as for example, ethyl alcohol. The amounts of such organic liquid solvents included may vary particularly where as with alcohol it is miscible with water in all proportions.

Solutions of these quaternary ammonium compounds give an excellent firming action on the protein of the dead body in relatively short periods of time. To enhance such firming action one or more of the water-soluble inorganic salts

referred to above may be utilized, particularly in amounts from 0.5 to 20% by weight in the composition and these inorganic salts may be used either in the aqueous vehicles or in the aqueous vehicles containing an organic liquid solvent.

Many of the quaternary ammonium compounds are sufficiently soluble in water to be utilized at the concentrations indicated as embalming agents. If desired the temperature at which they are employed may be from 70° to 110° F., and such compositions may be used at the stated range of temperatures or other temperatures in the usual way that embalming compositions are employed.

As exemplary of compositions that may be used in accordance with the present invention, the following are given illustratively.

Example 1

Mix 5 pounds of the quaternary ammonium salt as above illustrated graphically with 95 pounds of water (city water or distilled water) at a temperature of 70° F. to 110° F. This mixture shall be clear when finished and shall not contain any undissolved particles.

Example 2.—Mix 5 pounds of the quaternary ammonium salt of Example 1 above with $\frac{1}{5}$ pound of sodium meta phosphate and enough water sufficient to bring the total to 100 pounds. In this case would be 94.5 pounds. This mixture shall be clear when finished and shall not contain any undissolved particles.

Example 3

Mix from 5 to 50 pounds of the quaternary ammonium salt as above illustrated graphically with 95 to 50 pounds of water (city water or distilled) at a temperature of 70° F. to 110° F. This mixture shall be clear when finished and shall not contain any undissolved particles.

Example 4.—Mix from 5 to 50 pounds of the quaternary ammonium salt of Example 3 with $\frac{1}{5}$ pound of sodium meta phosphate and enough water to make the total weight 100 pounds which in this case would be 94.5 to 49.5 pounds of water. This mixture shall be clear when finished and shall not contain any undissolved particles.

Example 5

Mix from 5 to 50 pounds of the quaternary ammonium salt as above illustrated graphically with 95 to 50 pounds of water (city water or distilled water) at a temperature of 70° F. to 110° F. This mixture shall be clear when finished and shall not contain any undissolved particles.

Example 6.—Mix from 5 to 50 pounds of the quaternary ammonium salt of Example 5 with $\frac{1}{5}$ pound of sodium meta phosphate and enough water to make the total weight 100 pounds. Which in this case would be 94.5 to 49.5 of water. This mixture shall be clear when finished and shall not contain any undissolved particles.

Example 7.—Mix from 5 to 50 pounds of the quaternary ammonium salt of Example 5 with 95 to 50 pounds of 95% (by volume) of ethyl

alcohol at 70° F. to 80° F. This mixture shall be clear when finished and shall not contain any undissolved particles.

Example 8.—Mix from 5 to 50 pounds of the quaternary ammonium salt as above illustrated graphically in Example 5 with 95 to 50 pounds of 95% (by volume) of acetone at 70° F. to 80° F. This mixture shall be clear when finished and shall not contain any undissolved particles.

Having thus set forth my invention, I claim:

1. An embalming material comprising from 5 to 50% of a tetra-organo substituted ammonium halide in an aqueous vehicle, the tetraorgano substituted ammonium halide having the formula

in which R₁ and R₂ are selected from the group of lower alkyls and aryl radicals, R₃ is selected from the group consisting of lower alkyl radicals, long chain alkyl groups, aryl groups, alkenyl, alkoxy, and aralkyl groups, Ha is halogen, and T is selected from the group consisting of aryl, long chain alkyl, R₄—X—Ar—O—Alkylene, where R₄ is selected from the group consisting of alkyl, aryl, aralkyl and halogen substituted aralkyl groups, the alkyl in the aralkyl and halogen substituted aralkyl groups being lower aliphatic radicals, Ar is a benzene residue, X is a bridging group, O is oxygen, and alkylene is a lower aliphatic alkylene group.

2. A composition as set forth in claim 1, in which the halide is lauryl dimethyl benzyl ammonium chloride.

3. A composition as set forth in claim 1 in which the halide is lauryl trimethyl ammonium bromide.

4. A composition as set forth in claim 1 in which the halide is lauryl dimethyl ethyl ammonium bromide.

5. A composition as set forth in claim 1 in which the halide is a mixture of lauryl dimethyl benzyl ammonium chloride, lauryl trimethyl ammonium bromide, and lauryl dimethyl ethyl ammonium bromide.

6. A composition as set forth in claim 1 which includes from 0.5 to 20% of a water-soluble, protein-precipitating inorganic salt compatible with the halide.

7. A composition as set forth in claim 1 which includes from 0.5 to 20% of a water-soluble, alkali metal sulfate as a protein-precipitating inorganic salt compatible with the halide.

5 8. A composition as set forth in claim 1 which includes from 0.5 to 20% of a water-soluble, alkali metal sulfite as a protein-precipitating inorganic salt compatible with the halide.

9. A composition as set forth in claim 1 which 10 includes from 0.5 to 20% of a water-soluble, alkali metal phosphate as a protein-precipitating inorganic salt compatible with the halide.

10 10. A composition as set forth in claim 1 which includes from 0.5 to 20% of a mixture of at least 15 two water soluble alkali metal salts from the sulfates, bisulfates, sulfites, bisulfites, phosphates and acid phosphates, as a protein-precipitating inorganic salt mixture compatible with the halide.

20 11. A composition as set forth in claim 1 which includes an organic liquid solvent miscible with water and compatible with the halide.

12. A composition as set forth in claim 11, in which the solvent is ethyl alcohol.

25 13. An embalming material comprising from 5 to 50% of a tetra-organo substituted ammonium halide in an aqueous vehicle, the tetraorgano substituted ammonium halide being a compound in which the organo groups are two lower alkyl groups, one long chain alkyl group and one aryl group.

30 14. An embalming material comprising from 5 to 50% of a tetra-organo substituted ammonium halide in an aqueous vehicle, the tetraorgano substituted ammonium halide being a compound in which the organo groups are three lower alkyl groups and one long chain alkyl group.
